UNITED STATES PATENT OFFICE.

CRIS LEE, OF PADUCAH, KENTUCKY, ASSIGNOR OF ONE-HALF TO P. G. REED, OF SAME PLACE.

SASH-HOLDER.

SPECIFICATION forming part of Letters Patent No. 319,275, dated June 2, 1885.

Application filed March 25, 1885. (Model.)

To all whom it may concern:

Be it known that I, CRIS LEE, of Paducah, in the county of McCracken and State of Kentucky, have invented a new and Improved 5 Sash Holder and Lock, of which the following is a full, clear, and exact description.

The object of my invention is to provide a new and improved device for holding a sash at any desired elevation, or locking it to prevent its 10 being raised.

The invention consists in the combination, with a casing, of a bolt in the same, a spindle in the casing, and an eccentric plug on the spindle for operating the bolt.

Reference is to be had to the accompanying drawings, forming part of this specification, in which similar letters of reference indicate corresponding parts in all the figures.

Figure 1 is a face view of my improved sash 20 holder and lock. Fig. 2 is a side view of the same. Fig. 3 is a sectional plan view of the same. Fig. 4 is a view of the inner side, the parts being detached.

On a plate, A, a circular cap or casing, B, is 25 formed, and in the top of the same a spindle, C, is journaled, which is bent at its top to form a handle, D.

The lower end of the spindle is passed into an aperture, E, in a plate, F, placed into a recess or cavity, G', in the under side of the 30 plate A, the under side of the plate A and of the plate F being flush.

A sliding bolt, G, is arranged in the casing B, and has a circular aperture, which receives

a plug, H, mounted eccentrically on the spindle C. The outer end of the bolt G is rounded, as shown.

The plate A is held by screws on the stop-bead L in such a manner that the rounded end of the bolt faces the inner surface of the side 40 rail, J, of the sash K.

When the handle D hangs down, the bolt G is withdrawn, and the sash can be moved up and down.

When the sash is to be locked in position, 45 the handle D is swung up and from the sash, whereby the bolt G is forced against the side rail of the sash and binds on the same, thus locking the sash in place.

The sash-fastener can be fastened to the 50 sash as well as to the casing.

Having thus described my invention, what I claim as new, and desire to secure by Letters Patent, is—

The combination, with the plate A, having 55 a recess, G', in its under side, and provided with a casing, B, of the plate F, placed in the recess, the spindle C, journaled in the top of the casing and in the plate F, and having a handle, D, the eccentric plug H on the spindle, and the bolt G, provided with an aperture for receiving the plug H, substantially as herein shown and described.

CRIS LEE.
